(57) **CLAIM**

The ornamental design for a crochet needle holding apparatus, as shown and described.

DESCRIPTION

FIG. 1 is a front elevation view of a crochet needle holding apparatus showing our new design;

FIG. 2 is a left side elevation view of the crochet needle holding apparatus;

FIG. 3 is a right side elevation view of the crochet needle holding apparatus; and,

FIG. 4 is a rear view of the crochet needle holding apparatus in use with a crochet needle.

The clip is shown broken away in the middle to indicate that it has no specific length.

The broken line showing of a crochet needle in FIG. 4 illustrates environment and forms no part of the claimed design.
